(57) **CLAIM**

The ornamental design for a toilet stool, as shown and described.

DESCRIPTION

FIG. 1 is a front, top, right side perspective view of a toilet stool, with the legs unfolded, showing my new design;
FIG. 2 is a rear, top, left side perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof;
FIG. 8 is a bottom plan view thereof;
FIG. 9 is an exploded front, top, right side perspective view of FIG. 1, with the feet detached; and,
FIG. 10 is a rear, top, left side perspective view in a folded configuration, thereof.

The broken lines shown in the drawings depict portions of the toilet stool that form no part of the claimed design.
